United States Patent Office

Des. 174,392
Patented Apr. 5, 1955

174,392

NECKLACE OR THE LIKE

Louis Kramer, New York, N. Y., assignor to Kramer
Jewelry Creations, Inc., New York, N. Y.

Application August 24, 1954, Serial No. 32,004

Term of patent 3½ years

(Cl. D45—16)

Fig. 1

To all whom it may concern:

Be it known that I, Louis Kramer, a citizen of the United States of America, residing in New York city, county of New York, and State of New York, have invented a new, original, and ornamental Design for a Necklace or the like, of which the following is a specification, reference being had to the accompanying drawing, forming part thereof.

Fig. 1 is a plan view of a necklace or the like showing my new design.

Fig. 2 is an edge view thereof.

The necklace is broken away for purposes of illustration.

I claim:

The ornamental design for a necklace or the like, substantially as shown and described.
